2,050,691

CLOSURE

Thomas Francis Evans, Ainsdale, Southport,
England

Application March 9, 1935, Serial No. 10,242
In Great Britain March 9, 1934

3 Claims. (Cl. 221—60)

This invention consists in closures which when closed give tight closure against extrusion, leakage or escape of the contents from containers for pastes, ointments, greases and liquids and are applicable also to containers for powders and while they may be used, are easily opened for extrusion or discharge of the contents of the containers. While presenting the said advantages, closures provided according to the invention can, similarly to some closure devices heretofore provided, be made with smooth or even external surfaces so that material expelled or discharged from the containers can be easily applied to brushes or wiped off in any other way, as for example for use or in the preparation of containers for packing after filling. Further, in the closures provided according to the invention, the movable parts are not easily removable from the parts with which they co-operate and so cork or other packings, if any be used, are prevented from escaping.

In a closure provided according to the invention for a container of any kind, there are provided a body member and a closure cap turnable upon and axially movable within limits in relation to a circular part of the body member, which are provided with spiral valve faces, counter parts the one of the other, to work against one another, and each of uniform inclination along the spiral and extending in not more than one turn and forming a stop by one end and in the spiral valve faces are provided outlets to be in communication when the stop on the closure cap is against the stop on the body member and taken out of communication by the closure cap being turned relatively to the body member so that the one stop is moved away from the other and are engaged the one with the other so that turning of the closure cap relatively to the body member will cause the spiral valve face of the closure cap to slide and to be tightened against the spiral valve face of the body member. The spiral valve face of the body member is formed as an end face of a circular part formed with one orifice or more extending through it from a place of communication with the interior of the container and opening as the outlet in the spiral valve face.

The spiral valve face of the closure cap may be provided by the material of the closure cap itself or by a piece of compressible or other material inserted or secured in it.

Illustrative embodiments of closure devices provided according to this invention are represented in the accompanying drawing. In this drawing,

Fig. 1 is a plan of a container with a closure device of one form provided according to the invention shown in the closed position. Fig. 2 is a side elevation of the upper part of the container with the body member of the closure device shown in Fig. 1. Fig. 3 is a plan of the parts shown in Fig. 2. Fig. 4 is a side elevation of the closure cap shown in Fig. 1. Fig. 5 is a view showing the inner face of the closure cap shown in Fig. 4 before being applied on the body member of the container. Fig. 6 is a section through part of the container and a closure device shown in Fig. 1, showing the closure device in the open position, the sections through the body member and closure cap being indicated by the lines 6—6 of Fig. 3 and Fig. 5 respectively. Fig. 7 is a plan of a container and closure device showing a closure device with another form of cap. Fig. 8 is a section through part of the container and closure device shown in Fig. 7, the section being taken on the plane indicated by the line 8—8 of Fig. 7. Fig. 9 is a section through a body member and part of a container and a closure device showing a closure device with a cap of still another form. Fig. 10 is a section through a closure device formed with a stopper for application in an orifice of a container. Fig. 11 shows a closure device in which the body member and closure cap are each formed with a plurality of outlet orifices. Figs. 12 and 13 are developments of the spiral valve faces of the body members and closure caps of the closure devices shown in Figs. 1, 2, 3, 6, 7, 8, 9 and 10.

A closure device provided according to this invention may be provided on a container of any form or may be formed as a separate device for application in or on a container. By way of example, Figs. 1, 2, 3, 6, 7, 8 and 9 of the drawing illustrate closure devices with the body formed on collapsible tubes and Fig. 10 shows a closure device formed as a stopper separate from and applicable to a container, as for instance a bottle.

In the closure device illustrated by Figs. 1, 2, 3, 4, 5 and 6, the body member 14 is provided as a circular part around which the closure cap 15 is applied. The end face of the circular part of the body member 14 is formed with a spiral valve face 16 extending in one turn around and lengthwise of the center line of the body member 14 and of equal inclination throughout and by one end forming a stop 17. An outlet passage 18 extending through the circular member 14 for communication with the interior cavity in the container 19 is formed so as to open in the spiral face 16. The circular part of the member 14 is

shown as in part cylindrical and with a groove 20 formed around the body member 14 adjacent to the cylindrical part. The closure cap 15 is formed with a spiral valve face 21 which is a counterpart of and made to work against the valve face 16 formed in the body member 14 and like it forms a stop 22 at one end and is formed with an opening 23 in position to uncover the outer opening of the outlet passage 18 in the body member 14 when the stops 17 and 22 are together and to be taken out of communication by the cap being turned to move the stop 22 away from the stop 17. The skirt or tubular part 24 of the cap 15 which is shown in Fig. 4 in the form prepared for, but before, application to the body member 14 is spun or pressed into the groove 20 in the body member 14 while the stop 22 is against the stop 17 so that the turned in or spun part shall form a rib 25 to hold the closure cap 15 in connexion with the body member 14 so that it can not easily be removed therefrom and to hold the spiral valve face 21 of the cap 15 so close to the spiral valve face 16 that while the cap 15 can be turned to move the stop 22 away from the stop 17, turning of the cap 15 a little more than sufficient to remove the opening 23 from the opening 18 shall suffice to cause the spiral valve face 21 to be pressed firmly against the spiral valve face 16. Thus in the turning of the cap 15 from the position in which the opening 23 in the cap 15 leaves uncovered the opening of the outlet passage 18 in the body member 14 to a position in which the valve face 21 of the cap 15 closes the outlet passage 18 in the body member 14, the valve face 21 is made to slide upon the valve face 16 and is pressed tightly against it so that there is ensured a tight closure which will prevent leakage of grease, cream or liquid or any other contents of the container provided with the closure device.

Figs. 12 and 13 show developments, in linear form and in section, of the valve faces 16, 21, Fig. 12 showing the position in which the outlet 18 in the valve face 16 is open and Fig. 13 showing the outlet 18 closed by the valve face 21.

Figs. 1, 4, 5 and 6 show the opening 23 in the cap 15 chamfered or made to widen outwards so as to facilitate clean wiping or brushing, as for instance in the use of a tooth brush with the container.

Figs. 7 and 8 show a construction generally similar to that shown in Figs. 1, 2, 3, 4, 5 and 6 but with a larger outlet hole 26.

Fig. 9 shows a construction in which the body member 14 of the closure device is formed generally as that shown in Figs. 1, 2, 3, 6, 7 and 8, but the closure cap is furnished with a spiral valve face 27 on a piece of compressible or other material 28 inserted in the cap 29 and secured therein in any manner appropriate so as to be prevented from being turned relatively to the cap 29 and by way of example Fig. 9 shows the material 28 secured in position by indentations 30 of the cap substance as by the formation of indentations 30 in the cap 29.

Fig. 10 shows a closure device formed as a stopper and constructed, so far as concerns the valve faces 16, 21 and essentially operative parts of the closure device, as in the case of that shown in Figs. 1, 2, 3, 4, 5 and 6 but with the body member 14 formed with an extension tube 141 with a flange 142 and provided externally with an annular plug 31 shown as tapering and secured in position between the flange 142 and an outwardly spun or expanded portion 143 of the end

of the tube 141. The annular plug 31 may be of any material appropriate, for example cork or india rubber.

Figs. 1, 2, 3, 4, 5, 6, Figs. 7 and 8, Fig. 9 and Fig. 10 show in each case a single outlet orifice in the body member of the closure device and a single opening in the cap used with it, but more than one hole may be formed in the body member or the cap of a closure device provided according to this invention, as for example as in Fig. 11 which shows a body member 14 formed with three outlet orifices 181 and a closure cap 15 formed with three holes 231, the closure device being shown in the closed position in which the orifices 181 of the body member 14 are closed by imperforate portions of the spiral valve face of the closure cap 15.

Obviously the outlet openings in the body member and the closure cap may be formed in any position which allow of the outlet opening or openings in the body member being opened and closed in movement of the spiral valve face of the cap upon the spiral valve face of the body member.

In radial section the spiral valve faces shown in the accompanying drawing are all straight lines but obviously they may be made of any radial section so long as the surfaces of the valve faces for co-operation are counterparts of one another.

Any appropriate material may be used in the formation of the body members and closure caps of closure devices according to this invention in correspondence with the purposes for which the closure devices may be intended; the closure caps may be made of any external form desirable and different means may be employed in different cases for connecting the closure caps with the body members of the closure devices and making them turnable thereon.

What I do claim as my invention, and desire to secure by Letters Patent is:—

1. In a closure for a container, a body member furnished with a circular part which at one end face is formed with a spiral valve face of uniform inclination along the spiral, said spiral extending in not more than one turn and forming a stop by the step at one end, said circular part being also furnished with an outlet formed through it to open at one end in the container and at the other in the spiral valve face; and a closure cap turnably and axially movable within limits in engagement with said circular part, said cap being furnished with a spiral valve face a counterpart of that on said circular part and of uniform inclination along the spiral, said inclination extending in not more than one turn and forming a stop by the step at one end and having an outlet in position to communicate with that in said circular part when one stop is against the other, whereby turning of the closure cap to take one stop away from the other will close the outlet in said circular part and tighten the one valve face against the other.

2. In a closure for a container, a body member having a circular part which at one end face is formed with a spiral valve face of uniform inclination along the spiral and extending in not more than one turn and forming a stop by the step at one end, said circular part being furnished with an outlet formed through it to open at one end into the container and at the other end, on the spiral valve face; and a closure cap turnable and axially movable within limits in engagement with said circular part and having a spiral

- valve face a counterpart of that on said circular part and of uniform inclination along the spiral, said spiral extending in not more than one turn and forming a stop by the step at one end, said valve face having an outlet in position to communicate with that in said circular part when one stop is against the other, whereby turning of the closure cap to take one stop away from the other will close the outlet in said circular part and tighten the one valve face against the other.
3. In a closure for a container, a body member furnished with a circular part which at one end face is formed with a spiral valve face of uniform inclination along the spiral, said spiral extending in not more than one turn and forming a stop by the step at one end, said circular part being also furnished with an outlet formed through it to open at one end into the container and at the other end, on the spiral valve face, and a closure cap turnable and axially movable within limits in engagement with said circular part, said cap being furnished with a piece of inserted material formed with a spiral valve face a counterpart of that on said circular part, said spiral being of uniform inclination along the spiral and extending in not more than one turn and forming a stop by the step at one end, said inserted material being formed with an outlet into said closure cap; and other inserted material in position to communicate with that in said circular part when one stop is against the other, whereby turning of the closure cap to take one stop away from the other will close the outlet in said circular part and tighten the one valve face against the other.

THOMAS FRANCIS EVANS.
